[57] CLAIM

The ornamental design for a desk drawer microfiche reader, as shown and described.

DESCRIPTION

FIG. 1 is a front, left side perspective view of a desk drawer microfiche reader showing our new design in a closed position;

FIG. 2 is a front, left side perspective view in an opened position;

FIG. 3 is a right side elevational view in a closed position; and

FIG. 4 is a right side elevational view in an opened position. The rear and bottom are not shown and are plain and unornamented.
